UNITED STATES PATENT OFFICE

2,392,544

TOILET SEAT

William Nyberg, Duluth, Minn.

Application April 8, 1944, Serial No. 530,197

2 Claims. (Cl. 4—235)

This invention relates to improvements in an auxiliary toilet seat particularly adapted for use in serving an infant.

The principal object is to provide a strong, simple and readily adjusted seat of this type.

Another object is to provide a dependable locking means for such a seat when in its cooperative position with another and larger seat.

Other objects and advantages may appear in the further description of the invention.

Referring now to the accompanying drawing forming part of this application and in which like reference characters indicate like parts;

Fig. 1 is a top plan view of one of the improved auxiliary seats as attached to an ordinary toilet seat, the latter being shown only in part thereof.

Fig. 2 is a central vertical section taken on the line 2—2, Fig. 1, and

Fig. 3 is an enlarged top plan view of the major and adjustable holding means for the auxiliary seat.

1 represents a fragmental portion of a common toilet seat with the remainder suggested, in dotted lines Fig. 1, to economize in space for the drawing.

2 represents the somewhat generally pear shaped body portion of the auxiliary or infant seat which may be of wood, plastic or other suitable material.

3, 4 and 5 represent upwardly arched metal holding clips carried by the infant seat and designed to overlappingly engage the inner and lowermost marginal arcuate edges of the larger seat, the one 5 being the largest and only adjustable one of the three and installed within a spring controlled holding unit mortised within the front end of the body 2 flush with the upper flat surface thereof. The upper flat metal covering plate of this holding unit is indicated at 6 and the holding screws therefor at 7. This holding unit for the major clip 5 is to permit of said clip being conveniently manually manipulated back and forth for ready application or removal of the infant seat to or from the larger seat, and will be described more fully later.

It is to be understood that the entire upper marginal area of the body portion 2 is flat and designed to fit snugly up against the under flat face of the larger seat 1 when in place therebeneath.

A foldable guard rail is provided for upstanding relation about the central opening of the infant seat and which comprises the base rail 8 supported slightly above the body 2 by suitable depending leglike members 9 which extend down-

wardly through the body 2 where each may be equipped with a wing or other form of nut for holding same in place, wing nuts being suggested simply for convenience in removal of the guard rail when no more required, as for example, when the infant approaches childhood or more mature age.

To each side of this base rail 8 are pivotally attached as at 10 and 11 one of the side members 12 of the approximately semicircular railing guard about the seat, one downwardly bent end 13 of which forms one pivotal connection with the base rail 8 while the other support is indicated at 14, it also being pivotally attached as at 11 to said base rail.

The rearmost arcuate portion 15 is also pivotally supported upon the base rail 8 by the members 16 and 17 surrounding the rail 8 as at 18 and 19 respectively and the peculiarly bent ends 20 23—23 of this portion 15 are so arranged as to temporarily lockingly engage the downwardly bent ends 22—22 of the aligned side guard member 12—12.

This locking engagement just referred to occurs by the bent ends 23 of the guard portion 15 bearing upwardly tightly against the surrounding ends 22 of the sections 12 until it is forced sufficiently far backwardly to snap in under said extreme downwardly bent termini

30 22 to become temporarily interlocked therewith and there securely held against further rearward motion.

It however, may be readily forced forwardly again and downwardly to resting folded position 35 with its ends engaged upon opposite sides of the base rail 8 as clearly shown in dotted lines Fig. 1 of the drawing.

After the last mentioned positioning of the part 15, the side members 12 may be folded down upon the member 15 and be held snugly thereupon by the portions 12 snapping in under the opposed protruding sides of the loop or bight 24 formed centrally of the part 15 of the guard rail.

The complete device is thus foldable into a very neat and compact assembly for storage and handling purposes.

The holding unit for the major clip 5 comprises an elongated rectangularly shaped recess or mortise 25 formed in the upper face of the smaller end of the body 2 of the infant seat and which mortise is spaced slightly forwardly of an elongated extension 26 of the major circular opening in the body 2 of the auxiliary seat, this latter extension being for positive freedom downwardly 55 from the fore part of the user's body.

The extreme opposite ends of the mortise 25 are protected or lined each with a metal strip or buffer 27 and through which the rectangularly shaped pitman 28 is reciprocably mounted and extends at both ends beyond that portion of the body 2 adjacent same as clearly seen in Fig. 1 of the drawing.

The pitman 28 is installed centrally of the mortise 25 and adjustably carries within the slot 29 therein the major holding clip 5 before referred to.

This pitman has fixed thereto the cross piece 30 which extends transverse same and located within the mortise 25, and there forms abutments for the two like expansive helical springs 31-31 upon either side of said pitman which normally tend to urge the clip 5 tightly against the front innermost marginal edge of the larger seat to which the auxiliary seat is applied as the opposite ends of the springs 31-31 abut the buffer strip 27 adjacent said edge.

The outer or foremost end of the pitman 28 is provided with a relatively long narrow and substantially flat handle portion 32 for comfortably contacting the ball of the palm of the hand of the operator manipulating same while preferably the middle and next finger of the same hand are engaged one upon each side of the opposite protruding end of the pitman.

Thus when the hand is pinched together or being closed, the clip 5 will be manipulated for the desired engagement with or disengagement from the larger seat.

The clip 5 is provided with sufficient extension of stem 5', see Fig. 2, for reception of a wing nut 33 to hold it in any predetermined position longitudinally of the slot 29 in the pitman 28.

It will be noted that this peculiar grasping of the infant seat, with for example, the right hand while the operators left hand is holding up the

commonly hinged larger seat for reception thereof, the same may be accomplished with the greatest expedition and ease possible and the result obviously very satisfactory.

Having thus described my invention what I claim and desire to secure by Letters Patent is:

1. In a foldable auxiliary toilet seat for temporary attachment to a common toilet seat including a body portion having a flat outer marginal upper surface for engagement with the like flat inner marginal under surface of a common toilet seat; a three part normally upstanding guard about the central opening of said auxiliary seat, means carried by said body portion and pivotally supporting said guard parts in a manner to permit same being folded inwardly and downwardly over said central opening, integral means carried by one of said parts for cooperatively holding said three parts firmly together when thus united in either of their selectable adjusted positions and manually operable means for temporarily holding said auxiliary seat in cooperative relation to said common toilet seat.

2. In an auxiliary toilet seat for temporary attachment to a common toilet seat; a body portion having a substantially circular opening therein terminating at the front end of said body portion in a somewhat radially disposed channel shape, a major upstanding clip for holding engagement against said common seat, spring controlled means for supporting said clip, means for adjusting said clip in relation to said supporting means, hand hold means associated with said supporting means for convenient operation in conjunction with the end terminal wall of said channel shaped portion of said opening, and other fixed holding clips carried by said body portion about said opening.

WILLIAM NYBERG.
